ROOM THERMOSTAT OR SIMILAR ARTICLE

Albert E. Baak, 640 Ocampo Drive, Pacific Palisades, Calif.

Filed June 20, 1960, Ser. No. 61,043

Term of patent 14 years

(Cl. D52—7)

FIG. 1.

FIG. 2.

FIG. 3.

Fig. 1 is a front elevational view of a room thermostat, showing my new design;

Fig. 2 is a bottom plan view thereof; and

Fig. 3 is a perspective view thereof.

The essential features of my design reside in the portions shown in full lines.

I claim:

The ornamental design for a room thermostat or similar article, substantially as shown and described.
